UNITED STATES PATENT OFFICE.

MOSES L. RAU, OF CHICAGO, ILLINOIS.

MATCH-HOLDER.

1,357,250.

Specification of Letters Patent. Patented Nov. 2, 1920.

Application filed July 19, 1919. Serial No. 312,034.

To all whom it may concern:

Be it known that I, MOSES L. RAU, a citizen of the United States, and a resident of Chicago, in the county of Cook and State 5 of Illinois, have invented certain new and useful Improvements in Match-Holders, of which the following is a full, clear, and exact description.

The invention relates to match-holders.

10 The object of the invention is to provide an improved holding device which is adapted to be attached to an ordinary plate which serves as a receptacle for burnt matches, cigar and cigarette ashes and the 15 like. An advantage which is attained by providing a device which may be readily attached to and detached from an ordinary plate is that the plate can be easily washed and kept clean.

20 The invention consists in the several novel features hereinafter set forth and more particularly defined by claims at the conclusion hereof.

25 In the drawings: Figure 1 is a perspective of a device embodying the invention. Fig. 2 is a section showing the connection between the standard and the match-holder. Fig. 3 is a transverse section. Fig. 4 is a plan of the box-holder.

30 The invention is illustrated in connection with a holder 5 adapted to retain a box of matches 6 so the sides of the box containing the abrasive for lighting the match will be exposed. Usually a block 7 is secured on 35 the bottom of the holder to hold the match-drawer elevated, as shown in Fig. 1. This holder may be of any suitable or well-known construction.

40 The supporting device for the holder comprises a standard 8 formed of wire extending through a fitting and provided with an outwardly and downwardly curved leg 10 having a hook 11 at the lower end. A pair of legs 12 and 13 have their upper ends held and pivoted in sockets in the fitting 45 14 at the sides of the post 8 and each of these legs is of substantially the same shape as the leg 10, is extended outwardly and downwardly and is provided with a hook 50 11. All of the legs are preferably formed

of wire which has sufficient resiliency to cause them to grip the rim of an ordinary china plate 15 with sufficient force to be self-retaining and so that they will not be accidentally displaced. When the legs of 55 the supporting-device are placed in position shown by full lines in Fig. 1, the hooks thereon will grip the margin of the plate 15 and support the holder centrally above the plate. When it is desired to separate 60 the holder from the plate so the plate may be easily washed or to facilitate cleaning of the holder or to pack or store the latter, it is only necessary to force the legs together as indicated by dotted lines in Fig. 1. 65 If desired, the legs may be sprung around the margin of the plate. If desired, the holder can be separately used because the legs can rest on a table. The hooks 11 are usually covered with rubber tips to prevent 70 them from scratching the china and to aid in gripping the plate.

The invention exemplifies an improved supporting device for a holder which is adapted to be used in connection with an 75 ordinary china plate and which can be readily detached therefrom when desired.

The invention is not to be understood as restricted to the details set forth, since these may be modified within the scope of the 80 appended claims, without departing from the spirit and scope of the invention.

Having thus described the invention, what I claim as new and desire to secure by Letters Patent, is:

1. The combination with a holder of a fitting connected to said holder and provided with sockets, and a series of resilient legs having their upper ends separately held in and pivoted in said sockets, all of 85 said legs being provided with hooks for detachably gripping the margin of a plate.

2. The combination with a holder of a supporting device comprising a post, a fitting around the post, a resilient leg on the 90 post and a plurality of resilient legs pivoted to the fitting, all of said legs being provided with hooks for detachably gripping the margin of a plate.

MOSES L. RAU.
